TO HOOPPAW MANUFACTURING COMPANY, OF ST. LOUIS, MISSOURI, A CORPORA-
TION OF MISSOURI.

DOOR FASTENER.

Application filed September 17, 1923. Serial No. 663,126.

This invention relates to fasteners and latches, and more particularly to a fastener for doors of automobile bodies and the like, but not necessarily limited to such application and use. The present invention is a direct improvement upon that disclosed in our pending application Serial Number 526,488, filed January 3, 1922, and has for its objects to simplify and make more practical the general structure in order to facilitate manufacture and installation of the fastener; to provide a novel outside operating handle construction and arrangement so as to secure ease of operation and at the same time provide for simplicity and nicety of adjustment; and to attain certain further advantages as will more fully appear in the following description.

The invention consists in the parts and in the combinations and arrangements of parts as hereinafter set forth and pointed out with particularity in the appended claims.

In the drawings,—

Figure 1 is a fragmentary view, in elevation, of the adjacent upper corner portions of the door and side of an ordinary automobile body, with parts of the upholstery removed to expose the body-plate of the fastener so as to show how it is mounted;

Figure 2 is a top edge view of the door and adjacent side portions of the automobile body, with the fastener installed as shown in Figure 1;

Figure 3 is a fragmentary view, partly in edge elevation and partly in vertical cross-section, of the door, showing manner of connecting the outside operating handle with the inside actuator for the latch member;

Figure 4 is an inner face view of the body-plate and mechanism mounted thereon;

Figure 5 is a top edge view of the parts shown in Figure 4;

Figure 6 is a side edge view of the parts shown in Figure 4;

Figure 7 is an outer face view of the striker-plate or keeper-bracket detached;

Figure 8 is an edge view of the latter;

Figure 9 is a cross-section through the door-post, showing the striker-plate or keeper-bracket attached;

Figures 10 and 11 are detail views of the outside operating handle detached;

Figures 12 and 13 illustrate a modification of the outside operating handle;

Figure 14 illustrates a further modification of the outside operating handle; and

Figures 15 and 16 illustrate a still further modification of the outside operating handle.

Referring now to the drawings, the numeral 1 designates the door and the numerals 2 and 3, respectively, the adjacent side portions of an ordinary automobile body. The door is hinged, as at 4, in the usual manner, so as to swing outward in opening. As shown (see Figure 2), the meeting edges of the door 1 and the door-post 5 are rabbed correspondingly, as at 6, 6^a. The inner face of the door (see Figure 1) is provided with the usual upholstery panel 7, part of which latter is broken away to expose the top rail 8 and end rail 9 of the frame of the door, to which rail members the body-plate 10 is attached by the screws 11. In this connection, it may be here stated that the body-plate structure and the manner in which it is fastened to the door serves as a gusset-plate or reinforcement of the door-frame and obviates the necessity for providing the latter with the usual supplemental supporting block or frame member for the fastener, and at the same time it minimizes the cutting away or mortising of the door frame to accommodate the mechanism.

A part of the upholstery 12 of the body of the automobile is also shown removed to expose the door-post 5 in the region where the striker-plate or keeper-bracket 13 for the fastener is attached. The keeper comprises essentially a suitable bracket member 13, which, as shown, is preferably an angle-plate provided with apertures 14 in one of its flanges (see Figure 8) for the reception of screws or bolts 15 (see Figure 9) by which it is attached to the door-post. Preferably, this flange is countersunk into the door-post so that the outer face of the flange is substantially flush with the face of the door-post at the base of the rabbet, the rib or bead portion being cut-away, as at 6^b, to make clearance for the flanged box extension 10^a of the body-plate 10, which said extension is of width and depth corresponding to the width and depth of the rabbed portion of the door. On the other flange or striker-plate portion of this keeper-bracket is a stud 16 having a transverse groove or notch 17 and a tapered end portion 18.

The body-plate 10 is provided with an aperture 19 to receive said stud 16 when the door is closed. This aperture is of a diameter to receive the stud preferably with a 5 rather snug fit, particularly the cylindrical base portion of the stud. That is to say, with practically little or no play laterally of the stud.

On the body-plate 10 is a supplemental 10 plate 20 having an aperture of the same size as and registering with the aperture 19. This plate 20, which is provided principally as a reinforcement, may be attached to the body-plate 10 in any desirable manner, but, 15 preferably, it is provided at three places, as shown, with lugs 21 which are turned at right angles to the body portion of the plate and are of a length sufficient to enter apertures provided therefor in the body-plate 20 10 and in which apertures said lugs are riveted securely.

The supplemental plate 20 has a marginal flange 22 which abuts a marginal flange or the wall 23 of the box-extension 10^a of the 25 body-plate 10, said flange or wall 23 being provided for attachment to the end of the door and said flange 22 affording a reinforcement for relieving the flange or wall 23 of thrusts and strains. This supplemental 30 plate 20 is further provided with an aperture registering with a like aperture in the body-plate 10 to receive and have riveted or otherwise fastened therein the reduced end portion of a shouldered pivot-stud 24 35 for a rocking lever or latch member 25 whose end portion works in a slot provided therefor in said flange 22 of the supplemental plate 20 as indicated by dotted lines, as at 26, in Figure 4.

40 The latch member 25 has an angular extension 25^a, the end portion of which is turned up to constitute a lug 27, one edge portion of which latter is bevelled or inclined, as at 28, to afford a cam face. The 45 opposite edge portion of the lug 27 is provided with a notch 29 to receive the end portion of one leg 30 of a spring element whose middle portion is looped and coiled, as at 31, and whose other leg 32 is engaged in a 50 notch 33 in the edge of a lug 34 which is turned up from the supplemental plate 20.

The looped middle portion 31 of the spring is overhung by a hooked lug 35 extending up and outward from the margin of 55 the latch member 25 and through said loop of the spring with ample clearance and looseness to avoid binding and yet aid in retaining the spring in place.

The spring is constantly under tension 60 and, its legs 30 and 32 acting in opposed relation upon the respective lugs 27 and 34, holds the latch member 25 yieldably in normal position and restores it to such position after each operation thereof. When in normal 65 position, the edge portion of the latch

member 25 crosses the aperture 19 chordwise (see Figure 4) so as to enter the groove or notch 17 of the keeper-stud 16 when the latter has entered the aperture 19 as the door is closed. In this connection, it may 70 be here stated that, as the tapered end portion of the stud enters the aperture 19, the latch member 25 is rocked to clear said aperture, and as the groove or notch 17 is brought beyond the inner face of the plate 20 the 75 latch member snaps into said groove or notch by the action of the spring. The relative width of said groove or notch and thickness of the latch member is such that said latch member readily enters, more or less 80 play being provided for this purpose as may be desired. So, too, the inner wall of the groove or notch 17 is preferably bevelled or inclined, as at 17^a, to further insure the entering of the latch member into the groove 85 or notch.

Pivoted between ears 36, struck up from the body-plate 10, as shown in Figures 4 and 6, is an operating lever 37, at one end of which latter is an angular projection 38 normally engaging the cam face 28 of the extension 25^a of the latch member 25. At the opposite end of the lever 37 is a push-button 39 which projects normally through an opening 40 in the body-plate 10. As shown, 95 this push-button is cupped or has its marginal portion flanged, as at 41, and the opening 40 also has a surrounding flange 42 whose upper portion 43 is preferably deeper than the remainder thereof, while the lower portion is cut-away or slotted, as at 44, to provide clearance for the lever 37.

The flange 42, which is provided to afford a guard about the edge of the opening 40, is 100 preferably drawn up as an integral part of the body-plate 10, as shown, but, obviously, it may be made as a separate piece and attached to the body-plate according to any usual or approved practice.

When the push-button 39 is pressed, the 110 operating lever 37 is rocked and the latter, in turn, by its engagement with the cam portion of the latch member 25, rocks said latch member so as to move it out of engagement with the keeper-stud 16 and clear of the aperture 19, this movement being arrested by the latch member coming in contact with the upper end of the slot 26 in the flange 22 of the supplemental plate 20. When the push-button is relieved of pressure thereon the 120 spring, of course, restores to normal position the latch member and the several parts above noted which were operated therewith, the lever 37 at this time coming to rest against the inner face of the body-plate 10 and the latch member 25 nearly but not touching the lower end of the slot 26.

Mounted pivotally, as at 45, on an ear 46 struck up from the supplemental plate 20, is a second operating lever 47 having a bev- 125

elled end portion 48 to normally engage an inclined cam projection 49 on the extension 25^a of the latch member 25 adjacent to the lug 27. The opposite end portion of this lever 47 is slotted, as at 50, to receive the 5 looped or hooked end portion 51 of a screw-threaded connecting stem or member 52, which latter enters a screw-threaded bore 53 in the inner end portion of the connecting stem 54 of an outside operating handle 55.

The handle 55 is hingedly attached, as at 56, to a lug 57 projecting from the outer face of an escutcheon member or plate 58, which latter is provided with apertures 59 to receive screws 60 for attaching it to the outer face of the door. The handle is slotted to receive the lug 57, and in the lower portion of the slot is received the outer end portion of the connecting stem 54, which latter is 15 hinged to the handle proper, as at 61. In the escutcheon is an aperture 62 to cooperate with an opening 63 in the door through which the stem 54 projects inward to engage the stem 52, said openings 62 and 63, of course, being of somewhat larger diameter 20 than the stem, so as to afford sufficient clearance to permit the necessary swing of the connected stems 52 and 54 when the outside operating handle 55 is operated.

As shown, the handle 55, escutcheon 58, and stem 54 are assembled to constitute a unitary outside operating handle structure separate from the mechanism which is mounted on the inner side of the door. This 35 facilitates installation of the fastener and handle, and the adjustment of the stem connection between the latch-operating lever 47 and outside handle 55. That is to say, the body-plate 10 with the working parts of the mechanism assembled thereon is mounted on the inner side of the door, the opening 63 in the door, of course, being prepared to receive the screw-threaded stem 52 which is projected outward in said opening 63 to be 40 engaged by the outside operating handle 45 stem member 54.

After the body-plate 10 is mounted and the keeper or striker-plate correspondingly mounted on the door-post so that its stud 50 16 enters the opening 19 in the body-plate when the door is closed and it having been ascertained that the mechanism is functioning properly, the outside operating handle is applied by directing the stem member 54 inward in the opening 63 in the door so as to 55 engage the stem member 52. By turning the handle assembly complete the stem member 54 is screwed on the member 52 until the inner face of the escutcheon plate 58 is 60 brought into contact with the outer face of the door and all looseness or end play in the connection afforded by the members 52 and 54 between the actuator lever 47 for the latch member 25 and the handle 55 is taken up, 65 but without disturbing the normal position

of the inside push-button 39. This adjustment being effected the escutcheon member 58 is secured to the door by the screws 60. Consequently, the adjusted relation of the handle assembly is thereby maintained, and 70 should any further adjustment be necessary, either to tighten or loosen the link connection afforded by the member 52 and 54 between the lever 47 and handle member 55, the same may be readily accomplished by 75 removing the screws 60 and rotating the handle assembly in either direction, as the case may be, the screw-threads on the member 52 and 54 being, of course, relatively fine so that a single turn of the member 54 on the member 52 will only slightly lengthen or reduce the length of the linkage. In this way a very fine adjustment may be effected at will, both for taking up all looseness so as to prevent rattling of the handle and to take 85 care of doors of different thicknesses.

To open the door from the outside it is only necessary to grasp the handle member 55, which is in effect a lever of the second order, and swing it outward on its fulcrum 56, thereby pulling the linkage 52, 54, and rocking the actuator lever 47, the latter in turn rocking the latch member 25 and moving it clear of the notch in the stud 16, the parts being restored to normal position by 90 the spring which presses the latch member just as hereinbefore pointed out in connection with the operation of the latch member by the actuation of the inside push-button 39 and its attached lever 37.

The grasping portion of the outside operating handle 55 may be formed and designed in various shapes. As shown in Figures 2, 3, 10 and 11, it is of the pendent type, of hooked form, which is readily grasped and 105 conveniently manipulated, the end of the handle normally terminating close to but, preferably, not touching the face of the door, thereby presenting no projections on which clothing might be liable to catch, and of its 110 very nature indicating that the handle is to be pulled rather than turned or twisted in the operation of opening the door.

In Figures 12 and 13 the handle is of the "T" or cross-bar type, while in Figure 14 it is of the pendent, straight bar, drop type. A further modification is illustrated in Figures 15 and 16, in which case the handle is of the substantially horizontal or slightly inclined loop or spade-handle type. Obviously, the grasping portion of the handle may be still further modified without departing from the spirit of the present invention.

In practice, the stud 16; the reinforcing plate 20, particularly in the region about the aperture 19 which receives said stud 16; the latch member 25; and the cam portions of the actuator levers 37 and 47, are case-hardened obviously to minimize wear of the parts. So, too, the groove 17 in the stud 16

is preferably of a depth so that, normally, the edge of the latch member 25 does not touch the bottom of the groove when engaged. By this provision and also in that the latch member 25 normally does not touch the lower end of the slot 26 in the flange 22 of the reinforcing plate 20, should any wear occur on the cam faces, and which would be very slight, if at all, even after 10 long use, such wear would be taken up by the action of the spring pressing the latch member against the cam extension of the lever 37, the clearances, as above pointed out, permitting it. Consequently, looseness 15 and rattling of the parts is prevented. Furthermore, the stud 16 fitting the aperture 19 snugly so that there is very little or no play transversely, this clearance between the bottom of the groove 17 and the latch member 20 25 makes it practically impossible that the latter will be jarred and jolted out of engagement in the groove from the shocks to which an automobile body is subjected in use.

25 Aside from the ease in which the lock and outside operating handle may be installed on a car, there is the further advantage in that the door may be closed without undue force or slamming, and, when closed, the 30 door is held securely against accidental opening. Also, the door is easily and conveniently opened, at will, by merely pressing the inside push-button or pulling the outside handle. Then again, the construction and 35 arrangement is such that the usual heavy rubber bumpers heretofore required in connection with the use of the ordinary sliding-bolt fasteners are unnecessary with the present fastener, but only relatively small sound-deadeners need be used in place thereof and in some cases none may be required at all. Also, the effect of the tapered end of the 40 stud 16 entering the aperture 19 is to guide the door into closed position and thereby 45 obviates the necessity for the usual dove-tail or separate special door-guide heretofore generally provided for the purpose in connection with the old style locks. Furthermore, the dowel-like effect of the stud when 50 the door is closed serves to support the door in every direction transversely of the stud and thereby relieves the hinges of much weight and strains thereon incidental to the weaving motion of the door while the car 55 is running. Sagging of the door is prevented and by locking the door to the pillar or door-post, as afforded by the engagement of the stud in the aperture 19 of the body-plate, the body of the car is tied all around 60 so that strains thereon are distributed throughout and the possibility of the frame racking loose is prevented or at least greatly minimized.

In some cases, particularly on enclosed 65 bodies, it is desirable to have the fasteners

equipped with a fastening device which may be set from the inside of the car to prevent the door being opened from the outside. In the present case, therefore, a member 64 is hinged on the inner face of the body-plate 70 10 and adapted to engage the extension 25^a of the latch member 25 (see Figures 4 and 6, particularly). As shown, this member 64 has an arcuate end portion 65 which swings just clear of the edge of the extension 25^a 75 when the latter is in normal position, a shoulder 66 being provided on the member 64 to engage a shoulder on the extension 25^a where the lug 27 is turned up therefrom, thereby affording a stop to limit the travel 80 of the member 64 when it is moved into engagement with the extension 25^a.

The member 64 is mounted on a stub-shaft 67 rotatable in an aperture provided therefor in the body-plate 10 and having on its outer 85 end portion a suitable handle 68 for manipulating it, and a suitable friction-washer 69 being provided on the shaft between said handle 68 and the outer face of the body-plate 10.

90 By turning the member 64 to abut the extension 25^a obviously the latch member 25 cannot be rocked. Therefore, neither the inside push-button nor the outside handle can, under this condition, be operated. In 95 the employment of such fastening device, it is customary on cars having two or more doors, to provide all doors except one with fasteners so equipped, and the sole door for exit and entrance with a suitable pillar lock 100 or some other key-locking device or cylinder operable from outside the car, when, of course, the other doors are fastened from the inside as just above set forth.

105 It is also noted in further reference to the peculiar outside handle structure, that the handles are always maintained in their original parallel alignment on the body of the car, in contradistinction to the usual handles which have to be rotated or twisted in opening the doors and in which cases the handles often stick in their operated positions or do not return to full normal position, due to binding of the handle stem or shank or the latch-bolt of the fastener not returning to 110 its normal projected extent when the door is closed. That is to say, the handles of the present invention avoid this disadvantage and preserve the original fanciful lines in the body design.

115 What is claimed is:

1. In a door fastener, in combination with a component latch-releasing element having a link member hingedly-attached at one end thereto, the opposite end portion of said link member being free, of a separate unitary operating handle assembly, including an escutcheon member for attachment to the face of the door, said escutcheon member having a transversely-apertured lug on its outer face, 120

- a handle member having a portion slotted to receive said lug on said escutcheon member and a pivot-pin rotatable in the aperture of the lug, said slotted portion of the handle member normally abutting said escutcheon member, and said handle member having an offset grasping portion, and a link member hinged at one end in said slotted portion of the handle member and being projected through an aperture provided therefor in said escutcheon member with sufficient clearance to permit swinging of the connected link and handle members, said second mentioned link member having its free end portion arranged and provided for longitudinally-adjustable interlocking engagement with the free end portion of said first mentioned link member.
2. In a door fastener, in combination with a keeper member for attachment to the door post and having a flange overlapping the inner edge portion of the door and a stud of round cross-section on said flange projecting towards the meeting inner face of the door, said stud having a tapered end portion and a transverse groove between its base and said tapered end portion, a body-plate for attachment to the inner side of the door and having an aperture to receive said keeper stud with a relatively close fit, a latch member comprising a spring-pressed rocking lever having a stud-engaging portion normally overlapping said aperture chord-wise and enterable in the groove in said keeper stud, said latch member also having a cam portion, an actuator-lever having a cam portion cooperating with the cam portion of said latch member, a push-button on said actuator-lever operable from the inside of the car, a second actuator-lever having a cam portion cooperating with a second cam portion on said latch member, a link member hingedly-attached at one end to said second mentioned actuator-lever and having its opposite end portion screw-threaded, an escutcheon member for attachment to the outer face of the door, a handle-lever hingedly-attached to said escutcheon member, and a link member hingedly-attached at one end to said handle-lever and having its opposite end portion screw-threaded as a counterpart of said first mentioned link member whereby to be longitudinally-adjustably engaged therewith.
3. In a door fastener, in combination with a keeper member for attachment to the door post and having a flange overlapping the inner face of the door and a rigidly mounted, horizontal, cylindrical stud projecting substantially perpendicularly from the outer face of said flange, said stud having a tapered end portion and a transverse groove between its base and said tapered end portion, the inner wall of said groove being upwardly flaring, a body-plate for attachment to the inner face of the door, said plate having an aperture for the reception of said stud of the keeper member, and a latch member movably mounted on the body-plate and having a portion normally overlapping said aperture substantially chord-wise and being enterable in the groove in said stud of the keeper member.
4. In a door fastener of the character described, a keeper member for attachment to the door post and having a stud substantially perpendicular to the inner side of the door in the closed position of the latter, said stud having a tapered end portion and a transverse groove between its base and said tapered end portion, a body-plate for attachment to the inner side of the door, said plate having an aperture for the reception of said stud of the keeper member, a latch member comprising a rocking lever having a portion normally overlapping said aperture substantially chord-wise and being enterable in said groove in the stud of the keeper member, means including an operating handle for actuating said latch member, and a locking device on said body-plate and operable from the inside of the car for locking said latch member in normal position at will.
5. In a door fastener of the character described, a keeper member for attachment to the door post and having a stud substantially perpendicular to the inner side of the door in the closed position of the latter, said stud having a tapered end portion and a transverse groove between its base and said tapered end portion, a body-plate for attachment to the inner side of the door, said plate having an aperture for the reception of said stud of the keeper member, a latch member comprising a rocking lever having a portion normally overlapping said aperture substantially chord-wise and a counter-portion having a cam face, an actuator-lever having a cam portion cooperating with the cam face of said latch member, an operating handle for said actuator-lever, and a locking device on said body-plate comprising a pivoted arm movable into engagement with said latch member in counter-relation to the cam portion thereof and an operating handle operable from the inside of the car for manipulating said locking device at will.
6. In a door fastener, in combination with a body-plate securable to one face of the door, a latch-releasing element on the inner face of said body-plate, a link member hingedly attached at one end to said latch-releasing element whereby to swing universally with respect thereto, the opposite end portion of said link member being free, of a separate unitary operating handle assembly, including an escutcheon member for attachment to the opposite face of the door, a handle hinged thereon, and a link member hinged at one end to said handle and having

- its opposite end portion arranged and provided for longitudinally-adjustable interlocking engagement with the free end portion of said first mentioned link member.
- 5 7. In a door fastener, in combination with a body-plate securable to one face of the door, a latch-releasing element on the inner face of said body-plate, a link member hingedly-attached at one end to said latch-releasing element whereby to swing universally with respect thereto, the opposite end portion of said link member being screw-
- threaded, of a separate unitary operating handle assembly, including an escutcheon member for attachment to the opposite face of the door, a handle hinged thereon, and a link member hinged at one end to said handle and having its opposite end portion screw-threaded as a counterpart of and being longitudinally-adjustably engageable with the screw-threaded end portion of said first mentioned link member. 15 20
